(57) CLAIM

The ornamental design for a hanging ornament, as described and shown.

DESCRIPTION

FIG. 1 is a front perspective view of a hanging ornament illustrating my design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines are for the purpose of illustrating environmental structure only and do not form part of the claimed design.
